FLUID LIFT CONTROL VALVE FOR
OIL WELLS

Thomas E. Bryan, Fort Worth, Tex.

Application March 18, 1949, Serial No. 82,215

8 Claims. (Cl. 103—233)

1

This invention relates to devices for flowing oil wells by fluid pressures, as by inducting into such wells gas under relatively high pressures from the earth's surface, and it has particular reference to especially designed valves arranged at different levels or stages in oil wells, and involves structure generally relating to that disclosed in U. S. Letters Patent No. 2,236,864, dated April 1, 1941, assigned to Thomas Bryan, and it has for its principal object the provision of a valve construction adapted to be disposed at predetermined spaced elevations along the fluid conduits of an oil well and adjusted for automatic operation by fluid pressures of different values to intermittently discharge well fluids from such well.

A further object of the invention is that of providing an arrangement of co-axial conduits by which the well fluids can be raised through one channel while suitable gas pressures can be applied through the other channel from the earth's surface to move the liquids flowing into the well from the production areas thereof, the natural pressures in said well having been depleted and are therefore incapable of raising the oil column to the earth's surface.

Yet another object of the invention resides in the provision of a tubing fitting for the installation of the valve assembly wherein is defined a receptacle for the latter adapted to protect the assembly from damage in running the tubing into and out of the well, and forming the valve housing to especially adapt the same for attachment in the receptacle to insure rigidity, projecting its greater length into the receptacle to prevent vibration and possible injury from similar factors.

It is an important object of the invention to provide a system of flow valves capable of installation along a tubing string which functions as a flow conduit for well fluids while the well casing, closed at the bottom from the production area of such well by a packer, affords a channel into which gas pressures can be introduced to be admitted to the flow conduit through the said valve system in stages when acted upon by the gas pressures and in accordance with production capabilities of the well in which the installation is made.

An object of the invention is that of providing an economical medium for automatically producing oil from wells whose natural pressures are incapable of flowing the oil from such wells, and providing a system by which relatively high pressures can be inducted into the wells while preventing the application of excessive artificial

2

pressures to the producing oil sands through which the oil therein may be forced back into the formations, impairing the normal production capabilities of the well.

5 One object of the invention resides in the provision of a valve structure of the character described in which is embodied a closure control device whereby extended pressure contact areas are afforded to offset or nullify the effect of fluid velocities on the valve elements and insure greater efficiency in operation.

Broadly, the invention contemplates the provision of a valve embodying structural features which insures proper response to applied pressures sufficient to raise well fluids and is capable of utilizing the increased energies in gas at higher pressures when expanded to a lower pressure in the tubing.

While the foregoing objects are paramount, other and lesser objects will become manifest as the description proceeds, taken in connection with the appended drawings wherein:

Figure 1 illustrates, in vertical section on lines 1—1 of Figure 3, a valve structure embodying the invention, showing a body adapted to the removable or drop assembly illustrated in Figure 6.

Figure 2 is a fragmentary illustration, on lines 2—2 of Figure 3, showing one of the vertical grooves in the body member.

Figure 3 is a plan view of the valve shown in Figure 1.

Figure 4 is a transverse sectional view of the valve assembly taken on lines 4—4 of Figure 1.

Figure 5 is an inverted plan view of the invention.

Figure 6 illustrates, in elevation, a drop valve housing having a portion cut away to show the valve assembly illustrated in Figure 1.

Figure 7 is an elevational view of a stem assembly showing the piston member in vertical section.

Figure 8 fragmentarily illustrates, in vertical section, another type of body for the valve mechanism in which the dual arrangement of closures are employed on the stem.

Figure 9 fragmentarily shows, in vertical section, a modified arrangement of the closure members.

Figure 10 illustrates, in side elevation, a special fitting adapted for connection into the tubing string, and showing portions cut away to illustrate the valve installed therein.

Figure 11 is a plan view of the fitting shown in Figure 10.

Figure 12 is a transverse sectional view through the fitting on lines 12—12 of Figure 10.

Figure 13 is a vertical sectional view of a type

of fitting employed at the bottom of the tubing string for receiving the drop valve shown in Figure 6, and

Figure 14 is a vertical cross-sectional view of a well illustrating a typical installation and showing a typical time cycle device connected therewith.

While the embodiment of the invention is primarily a valve structure, it embraces a complete system of valves and flow conduits by which oil is produced from wells which would otherwise require the use of pumping equipment.

Production can thus be accomplished through a typical installation, such as that illustrated in Figure 14, in which a casing 10 is arranged in a well bore 11 and a string of tubing or flow conduit 12 arranged co-axially thereof. A packer 13 is installed near the lower end of the casing 10 and provides a seal about the tubing 12 defining an annular space 14 therearound inside the casing 10. A perforated tail pipe 15 extends below the packer 13 into the production area 16 of the well.

The well fluid is conducted to the earth's surface through the tubing 12 when acted upon by artificial gas pressures introduced into the space 14 in the casing 10 through a pressure line 17 in the casing head 18, the pressures being controlled by any conventional type of pressure regulator. A time cycle mechanism may also be employed to introduce pressures into the conduits at predetermined intervals, or as the well fluid flows into the bore 11 from the producing formation 16. Suitable flow pipes 19 and 20 may be provided for conveying the oil to storage from the head 18.

The valve structure employed in the invention and installed in the flow line or tubing 12 at properly spaced intervals, is housed according to the specific use to which the same is placed, as will become apparent by reference to Figures 1, 2 and 6 as compared to the structures shown in Figures 8, 9 and 10. The structure illustrated in Figure 1, particularly, is especially adapted to be installed in the removable or drop valve assembly shown in Figure 6 which is designed for installation in a special fitting shown in Figure 13 at the lower end of the tubing string 12 and just above the packer 13, as illustrated in Figure 14. This fitting may be categorically referred to hereafter as the "unloading chamber" through which all well fluids are discharged from the annular space 14 in the casing 10 after the packer 13 is set. After the "unloading" operation, the annular space 14 in the casing 10 being "dry," oil from the producing formation 16 is flowed upwardly through the tubing 12 to storage aided by gaseous pressures introduced into the annular space 14 and admitted to the tubing 12 in stages at different elevations to raise the liquid column.

In Figure 1 the valve assembly is shown enclosed within a housing 21 having a body portion 22, the housing being formed with threaded portions 23 and 24 above and below the body portion 22, while a tail portion 25 is defined below the lower threaded portion 24 of the housing 21. A central bore 26 is formed through the housing 21 and a sleeve 27 is arranged intermediate the ends thereof and has a central port 28 therethrough with seats 29 and 30 formed on each side. A stem 31 is arranged in the bore 26 and extends concentrically through the bore 28 of the sleeve 27, a closure 32 being formed on the stem 31 above the sleeve 27 and adapted to

engage the seat 29 thereon to close the port 28 under pressures entering the inlet 33 into the upper chamber of the bore 26 above the sleeve 27 therein.

A closure 34 is formed on the stem 31 below the sleeve 27 and is adapted to engage the seat 30 therein alternately with the closure 32 in closing the port 28 through the sleeve 27. The closure 34 is normally held against the seat 30 by a spring 35 arranged about the lower end of the stem 31 and which will yield under pressures applied through the inlet 33 previously referred to. A plug 36 is pressed or otherwise secured within the upper end of the housing 21 and functions to guide the upper end of the stem 31 which extends into a bore 37 to properly center the stem 31 in the bore 26 and guide the closures 32 and 34 to their seats 29 and 30.

The lower end of the bore 26 is interiorly threaded to receive an exteriorly threaded follower 38 which may be threaded into and out of the housing 21 against the spring 35 to increase or decrease the tension thereof thus controlling the amount of pressure required through the inlet 33 to displace the closure 34 from its seat 30. A lock-nut 39 is threaded upon the follower 38 whereby the latter is secured in its adjusted positions. An orifice 40 is provided concentrically of the follower 38 to discharge pressures from the chamber 41 within the follower 38 and the bore 26 in cooperation with another outlet passage hereinafter referred to.

As apparent in Figures 2, 3, 4 and 5 the body portion 22 is formed with a plurality of vertical grooves 42 which are partially enclosed by a sleeve 43 pressed upon the body portion 22 in a manner shown in Figures 1, 3, 4 and 5. By this means the pressures entering the housing 21 through the port 33 are effective on the element 34 to close the valve. The stem 31, shown in detail in Figure 7, has a free-floating piston 45 slidably arranged thereon below the closure 30 and against which the spring 35 exerts its tension to insure the positive operation of the stem 31 to close the lower seat 30 by the closure 34.

The valve assembly illustrated in Figures 1, 2, 3, 4 and 5 is housed within a removable casing 46 which has upper and lower sections 47 and 48 threaded upon the portions 23 and 24 of the housing 21. The upper section 47 has a rounded shoulder 49 at its upper end about which is arranged a plurality of ports 50. A spear 51 is formed on the upper end of the upper section 47 by which the assembly can be removed by a cable (not shown), the lower section 48 being substantially flat on the bottom and adapted to engage a supporting shoulder 53 formed in the bottom of a fitting 54, shown in Figure 13, by which it is adapted to be installed in the tubing string 12, in the manner shown in Figure 14, and which will presently be described in detail.

The fitting 54, illustrated in Figure 13, is swaged providing reduced portions 55 and 56 at each end, the larger body portion or shell 54 embracing a tubular sleeve 57 arranged concentrically of the member 54 having an interiorly threaded flange 58 formed at its lower end into which a tube (not shown) may be connected and which extends into the tail pipe 15. Tubular couplings 59 are arranged radially on the member 57 and extend through the walls of the body portion of the shell 54 and provide communication between the sleeve 57 and the annular space 14 within the casing 10. The fitting 54 is connected to the tubing 12 at each of its reduced

ends 55 and 56 by a collar 63. The upper rim 64 of the sleeve 57 is bevelled inwardly to expedite the seating of the drop valve assembly thereinto.

Above and below the valve housing 21, and the assembly illustrated in Figure 6, are arrangements of sealing rings or cups 62 and 63 arranged on the upper and lower sections 47 and 48 of the drop valve assembly to isolate the port 33 in the annular space defined by the reduced portion 64 intermediate the ends of the assembly, as shown in Figure 6, the opposing ends of the upper and lower sections 47 and 48 being tightly fitted against the collar 42 arranged about the body portion 22 of the valve housing 21. The couplings 59 provide communication between the annular space defined about the drop valve assembly within the member 57 and the space 14 within the casing 10.

A latch 65 is pivotally attached to the bottom of the drop valve by a pin 66 which is capable of being sheared when the drop valve assembly is removed by a wire line (not shown). The fitting 54 is installed in the tubing in the manner illustrated in Figure 14 near the packer 13. The latch 65 is adapted to drop into a slot which may be formed in the lower end of the sleeve 57 and at the bottom thereof just above the shoulder 53 therein upon which the drop valve assembly rests when seated. This arrangement will prevent the drop valve assembly from being displaced from its seat by pressures from the producing area 16 below.

In Figure 10 is illustrated a fitting 67 which is capable of being connected into the tubing string 12 by suitable couplings 68, in the manner illustrated in Figure 14. The member 67 is threaded on each end and is formed with a receptacle 69, as in Figure 10, to receive a valve assembly which is illustrated fragmentarily in Figures 8 and 9. Spaced above the receptacle 69 is an integral hood 70 affording further protection for the valve assembly arranged in the receptacle 69.

The valve assembly shown in Figures 8 and 9 is similar to the valve illustrated in Figures 1 through 5. It will become apparent, however, that the housing 71 in this latter structure does not have the sleeve or collar 43 thereon although its port 72 is formed in the polygonal head 73, as illustrated in Figure 8. A port 74 is formed in the housing 71 below the head 73 and the sleeve 75 therein and this port communicates with a port 76 in the wall of the fitting 67 providing communication between the valve housing 71 and the receptacle 69 when the assembly is installed in the manner illustrated in Figure 10. The upper end of the housing 71 is closed by a flanged plug 77 threaded into the member 71, and the upper end of the valve stem 78, arranged through the port 79 in the sleeve 75, operates within a recess formed within the plug 77.

The valve housing 71 is formed with a threaded portion 80 just below the head 73 by which the assembly is threaded into the upper end of the receptacle 69 so that the major portion of the housing 71 extends downwardly into the receptacle 69 and is thus protected against damage from vibration and other factors. On the stem 78 is a pair of closures 81 and 82 adapted to alternately engage the seats 83 and 84 in the sleeve member 75. A spring 85 is arranged about the lower end of the stem 78 to provide sufficient tension against the lower seating member 82 to retain the same normally against the seat 84, in

the same manner as that of the arrangement illustrated in Figure 1.

The valve structure shown in Figure 8 is modified, as illustrated in Figure 9, whereby the seating member 81 is eliminated from the stem 78, the latter extending only into the port 79 in the sleeve 75, and a ball 86 is provided for closing the port 79, by engaging the seat 83 in the upper end of the sleeve 75, and is capable of being raised by the stem 78 in the manner shown in Figure 9.

It is a prime object of the invention to lift the oil, as nearly as possible, in accordance with known physical laws, imposing the greatest force 15 at a point where it would be most effective. After installing a suitable number of valves in the tubing string, the fitting 54 having been attached at the bottom of the string, the "unloading" operation is accomplished by introducing gas pressures 20 into the casing 10 to force the well fluid therein into the tubing 12 through the coupling 59 in the "unloading chamber" or fitting 54. The drop valve assembly can then be installed through the tubing 12 from its upper end which may be normally plugged or have a system of gate valves 25 thereon (not shown) and the tubing sealed.

Such a method of discharging liquids from the casing 10 is desirable to prevent forcing the oil through the valves installed at spaced intervals 30 in the tubing 12 and thus avoid damage thereto through lodging sand, rocks, and other substances therein. Oil will rise from the producing area 16 into the tubing 12 and can be raised to the earth's surface by continuing to apply gas pressures 35 to the casing 10 to be admitted to the tubing through the valves therein.

In construction, as previously pointed out, the valve shown in Figures 8 and 9 is identical in principle with the structure illustrated in Figure 1, the primary difference residing in the respective housings. The lower end of each valve structure, the tail portions 25 and 71' being alike, are closed at their lower ends by followers 38 which have ports 40 therein. These elements are not shown in Figures 8 and 9.

In a typical installation the valves are installed with the lower valve elements 82 seated, under the pressure of the springs 85, as shown in Figures 8 and 9. With no pressure in the casing 10 or in the tubing 12 such positions of the stems with their closure elements are normal. As soon as the annular space 14 within the casing 10 has been unloaded, as previously described, the upper closure elements 32 and 81 on the stems 31 and 78, or the ball 86, will engage the seats 29 and 83 under gas pressures existing in the casing 10.

Oil rises into the tubing 12 from the producing area 16 through the tail pipe 15, and a standing valve (not shown) which may be threaded into the element 58 of the fitting 54 if desired, and submerges the valves. As the column of fluid increases its weight will exert sufficient pressure upon the pistons and the upper closure elements through the parts 40 and 74, respectively, to displace the same from their seats to admit gas pressures to the tubing and expel the liquid therefrom. The rapidly decreasing oil pressures within the tubing will enable the upper elements to be reseated under the gas pressures exerted upon the same.

As gas enters the lower body of the valve housing 71 the pressures become effective on the upper face of the piston 45 while the underside of the latter is exposed to the pressure of the oil column in the tubing 12 through the port 40.

Gas escaping through the port 74, when the piston is moved downwardly, lightens the oil column permitting the piston 45 to be depressed by gas pressures entering through the ported sleeve 27 or 75 and when a proper differential of pressures, for which the valve is set, occurs the upper seating element 81, or ball 86, will engage the seat 83 closing the valve against the gas pressures.

Each valve operates in this fashion until all fluid in the casing has been transferred into the tubing 12 through the fitting or chamber 54 whereupon the removable "drop valve" is installed, as previously described, the upper seating element 32 engaging the seat 29.

The well fluid may now rise into the tubing around the member 57 in the chamber 54 to a level which is determined by the gas pressures in the casing and the tension of the spring 35 whereupon the pressure of the oil column is effective through the ports 40 and 44 (or 40 and 74 as applied to the other valves) below the seating elements to force the upper seating element 32 (or 81), with the aid of the spring 35, off its seat and admit gas pressures to the tubing in the manner previously explained. When a sufficient quantity of the gas pressure has been passed into the tubing to lighten the oil column and lift the same to the surface, the gas pressure entering the ports 33 (Figure 1) and 72 (Figure 8) will become effective downwardly on the piston 45 to close the valve against the tension of the spring. The other valves above will function in like manner, successively, as the oil, or other fluids, reaches the proper height to submerge the valves and have sufficient weight to actuate the same.

It is apparent that the piston 45, which has been described as slidable or free-floating on the stem 31, will assume the position shown in Figures 1, 2 and 8 when the lower seating element 34 or 82 is against its seat and in such position will close the port 44 (Figure 2) or 74 (Figure 8) and close the same against oil pressure from the tubing. The piston 45 is relatively closely fitted in the chamber in the lower portion of the valve body and actually functions as a piston. Thus, oil pressures from the tubing is effective only on the bottom of the piston 45 while the lower element 34 or 82 is against its seat. When gas pressures in the casing reach a value suitable to overcome the back pressure of the oil in the tubing such gas pressures will be effective on the top of the piston to move the same downwardly relieving, to some extent, the tension of the spring 85 and opening the port 74 so that such pressures will pass into the tubing to raise the liquid column.

As the port 74 is initially cracked open enough gas or casing pressure will be admitted to the tubing to lighten the fluid column by aeration, as previously described, to permit the piston 45 to be further depressed against the tension of the spring 35 (Figure 1) or 85 (Figure 8) and free the stem so that the lower seating element can be moved further away from its seat to fully open the passage 28 or 79 and, at once, fully open the port 74 (Figure 8) or the port 44 (Figure 2) and flow the well.

It is to be understood that all of the valves have the same function and operate in an identical manner. The elements referred to in one structure, although having different character references, have similar functions. The seating elements, valve stems and springs operate in an identical manner.

Obviously, when the gas pressures in the casing and tubing are equalized no fluid can reenter the

casing through any of the valves for the reason that they remain closed, opening only when the casing pressure is greater, and under such conditions the passage of liquids therethrough is resisted.

5 Certain changes and modifications in the structure herein shown and described may be resorted to from time to time by persons skilled in the art without departing from the spirit and intent of 10 the invention or the scope of the appended claims.

What is claimed is:

1. In a flow valve for oil wells comprising a tubular housing for installation in a fitting in a well tubing, an inlet port in one end of said housing and an outlet port in its opposite end, a passage between said inlet and outlet ports, a seat formed on each end of said passage, a stem operating in said passage having opposing seating elements formed thereon alternately engageable 20 with said seats, a piston element closely fitting in said tubular housing and slidable on said stem and engaging the lowermost of said seating elements and normally closing said outlet port, a spring on said stem tensioning said piston element and yieldable to well pressures applied to said piston to open said outlet port and aid in moving said stem to open said passage and close the same.

2. In a gas flow valve for oil wells comprising a

30 tubular housing adapted for installation in a fitting connected in a well tubing, a gas inlet port in one end of said housing and an outlet port spaced from said inlet port in said housing, a passage between said inlet and outlet ports, a seat formed

35 on each end of said passage, a valve stem operating in said passage and having opposing seating elements formed thereon alternately engageable with said seats, a piston element slidably operating in the lower portion of said housing below said

40 passage and slidable on said stem to engage one of said seating elements, the said piston element being normally positioned to close said outlet port, a spring on said stem engaging said piston and yieldable to gas pressures on said piston to

45 open said outlet port and aid in moving said last named seating element to open said passage and close the same upon the occurrence of pressure differentials between said inlet and outlet ports.

3. In a gas lift device for oil wells and mounting

50 therefor, a well casing, a tubing in said casing, a tubular fitting connected at different levels in said tubing, a valve receptacle formed on said fitting having communication with the said tubing, a valve assembly threadedly supported in said fit-

55 ting and having a portion exposed to gas pressures in the casing, the said valve assembly comprising a housing, gas inlet and outlet ports in said housing, a passage formed axially on said housing between said ports and a valve seat on

60 each end of said passage, a valve stem operatively arranged through said passage, a pair of seating surfaces on said stem alternately engageable with said valve seats to close said passage, a spring on said stem normally retaining one of said seating

65 surfaces on its seat, a piston closely fitting in said housing and slidably arranged on said stem below said passage closing said outlet port and engaged by said spring and yieldable to gas pressures in

70 said casing to move on said stem whereby said pressures can actuate said stem to open said outlet port and close said passage until a predetermined pressure differential occurs between said

75 tubing and casing to reopen said passage.

4. In a device for raising oil in an oil well having a casing and tubing therein, a fitting connect-

ed at different levels in said tubing, a valve receptacle formed on said fitting and having communication with said tubing, a valve removably supported in said receptacle comprising a housing having gas inlet and outlet ports therein, a communication in said housing between said ports and a seat formed on each end of said communication, a stem operatively arranged through said communication and having seating elements thereon for alternately engaging said seats, a 10 spring in said housing associated with said stem exerting tension thereon to normally retain one of said seating elements against one of said seats, and a piston member slidable on said stem and slidably operating in said housing below the lowermost of said seating elements closing said outlet port and amenable to gas pressures to compress said spring whereby said pressures can actuate said stem to open said outlet port and close said communication until a predetermined pressure differential occurs between said casing and tubing to reopen said communication.

5. In a gas lift device for installation in an oil well, a tubing in said well, a fitting connected in said tubing and having a valve receptacle formed thereon and having communication with said tubing, a valve housing threadedly secured in said fitting to expose a portion thereof to gas pressures exteriorly of said tubing and having an outlet port theren in said receptacle, a gas inlet port in the exposed portion of said housing, a passage formed in said housing intermediate said inlet and outlet ports, a seat formed on each end of said passage, a valve stem operatively arranged through said passage and formed with seating surfaces alternately engageable with said seats to close said passage, a spring on said stem normally urging one of said seating surfaces to its seat, a sliding piston on said stem adjacent to one of said seating surfaces and closing said outlet port and engaged by said spring, and amenable to gas pressures to move on said stem against the tension of said spring whereby to open said outlet port and said stem can move to open said passage and close the same at the opposite end after a predetermined interval.

6. In a gas lift mechanism for admitting a lifting fluid to a liquid column in an oil well having a string of tubing and casing and a packer therein, a fitting connected in said tubing at spaced intervals and having a valve receptacle thereon, a valve housing having an opposing arrangement of seats and a communication between said seats installed in said receptacle on said fitting exteriorly thereof, a valve stem operable through said communication and having seating elements thereon adapted to alternately engage said seats, a spring in said housing associated with said stem capable of exerting a pressure thereon to normally retain one of the said seating elements against one of said seats, inlet and outlet openings in said housing for the passage of said lifting fluid, means slidable on said stem below said seating elements and closely fitting in said housing and engaged by said spring to close said outlet opening and amenable to gas pressures to compress said spring whereby said pressures can pass

through said outlet opening and actuate said stem to close said communication when a pressure differential occurs between the casing and the tubing.

5. A gas lift valve mechanism for lifting a fluid column in an oil well having a string of tubing and casing and a packer therein, a fitting in said tubing formed with a valve receptacle on one side communicating with said tubing through said fitting, a valve housing adapted to be rigidly supported in said receptacle and having communication therewith, gas inlet and outlet ports in said housing and a passage therebetween, opposing seats formed on the ends of said passage, a stem operatively arranged in said housing and through said seats, a pair of closure elements formed on said stem alternately engageable with said seats, a piston member closely fitted in said housing and slidably arranged on said stem below the lowermost of said closure elements closing said outlet port and aiding in the operation of said stem, tensioned means on said stem engaging said piston member for normally retaining the lowermost of said closure elements against its said seat whereby, when gas pressure is applied to said piston member, said outlet port is opened and tension on said stem is relieved and said stem can move to open said passage and close the same from the opposite end after a predetermined interval.

20. 8. In a gas lift mechanism for oil wells having a casing and tubing, a plurality of fittings spaced along said tubing, each having a valve receptacle exteriorly thereof open to said casing at one end, 25 a valve housing arranged in each fitting and having a portion exposed to gas pressure in said casing, a gas inlet port in said exposed portion and an outlet port in said housing open to said fitting through said receptacle, a passage between said ports providing communication between said ports and a seat at each end of said passage, a stem operatively arranged through said seats and having a pair of opposing seating surfaces formed thereon alternately engageable with said seats to close said passage, a tensioned piston element 30 closely fitting in said housing and slidably operating on said stem to normally close said outlet port and urge one of said seating surfaces to its seat and yieldable to pressure in said casing 35 whereby to open said outlet port and said pressure can force the opposite seating surface to its seat after a predetermined interval.
